UNITED STATES PATENT OFFICE.

EDWARD H. STEWART, OF PITTSTON, PENNSYLVANIA.

DESIGN FOR A CLASP.

SPECIFICATION forming part of Design No. 24,354, dated June 4, 1895.

Application filed March 18, 1895. Serial No. 542,263. Term of patent 14 years.

To all whom it may concern:

Be it known that I, EDWARD H. STEWART, a citizen of the United States, residing at Pittston, in the county of Luzerne and State of Pennsylvania, have invented and produced a new and original Design for a Clasp, of which the following is a specification, reference being had to the accompanying drawings, forming part thereof.

10 Figure 1 is a perspective view of a clasp, showing my design; and Fig. 2 is a sectional side elevation of the same.

15 The leading features of my design consist in the top cross bar A made approximately half round in section with the straight surface on top, the bottom cross bar B, the hook E formed at the front end of the frame D and a curved plate F extending from the

front of the hook to and over part of the straight top surface of the cross bar A. 20

Minor features of my design are the general frame D in the sides of which terminate the said cross bars A and B, and at the front of which the said hook E is formed, the rear end D' of the frame made round in section, 25 and the lug or projection C at or near the middle of the bottom cross bar and extending in an upward direction.

I claim—

20 The design for a clasp as herein shown and described. 30

EDWARD H. STEWART.
